(57) **CLAIM**

The ornamental design for a holder and holder support with pivotable arm-actuated suction membrane, as shown and described.

DESCRIPTION

FIG. 1 is a perspective view of an holder and holder support with pivotable arm-actuated suction membrane;

FIG. 2 is a right side view of the holder and holder support with pivotable arm-actuated suction membrane shown in FIG. 1;

FIG. 3 is a left side view of the holder and holder support with pivotable arm-actuated suction membrane shown in FIG. 2;

FIG. 4 is a front view of the holder and holder support with pivotable arm-actuated suction membrane shown in FIG. 1, FIG. 5 is a rear view of the holder and holder support with pivotable arm-actuated suction membrane shown in FIG. 1, FIG. 6 is a top view of the holder and holder support with pivotable arm-actuated suction membrane shown in FIG. 1; and,

FIG. 7 is a bottom view of the holder and holder support with pivotable arm-actuated suction membrane shown in FIG. 1.

The broken lines in the drawings illustrate portions of the holder and holder support with pivotable arm-actuated suction membrane which are not part of the claimed design. In the holder and apparatus holder support with pivotable arm-actuated suction membrane, the pivot arm is pivoted for actuating the suction membrane to firmly engage the apparatus holder with a smooth surface. The apparatus holder is used for holding an apparatus such as cell phone, a GPS or a tablet.
